FRITIOF STONEBERG, OF CHICAGO, ILLINOIS

INTERMITTENT OPERATOR FOR WINCHES

Application filed December 29, 1930. Serial No. 505,380.

This invention relates to jacks, winches and hoists having mechanism of the lever and ratchet type. In devices of this type, the ratchet is usually advanced step-by-step by a pawl which is actuated by a hand-operated lever. A detent secures the ratchet against accidental backward movement.

Winches of the ratchet and lever type have long been in use for tightening cables such as those employed in connection with the hand-operated brakes of railway cars. In such devices one end of the cable is usually wound on the drum or other power transmitting element connected to the ratchet of the winch.

With the old type of ratchet winch heretofore in use, the intervals of movement of the power transmitting element were uniform and, therefore, the cable or other attachment operated by the winch always moved a definite distance upon each complete stroke of the hand lever.

In some classes of work for which ratchet winches are employed, the load is initially small and then increases. For instance, in tightening a railway car brake, the slack in the cable is first taken up before the winch has any effect upon the brakes. So long as there is slack in the cable, the load on the winch is comparatively small and becomes appreciable only after the cable has been drawn taut. For such classes of work, it is desirable to have a winch with a differential speed, so as to be capable of a rapid take-up movement when the load is not appreciable.

The main objects of this invention are to provide a jack or winch of this type having improved mechanism for automatically imparting rapid take-up movements to the power transmitting element without altering the strokes of the lever; to provide improved manually controlled means for releasing the detent to permit reverse rotation of the power transmitting element when desired; and to provide a device of this kind which is particularly adapted for use in connection with the hand brakes of railway cars.

An illustrative embodiment of this invention is shown in the accompanying drawings, wherein:—

Figure 1 is a vertical section of a winch to which this invention is applied; part of the handle being broken away.

Fig. 2 is a transverse section, taken on the line 2—2 of Fig. 1.

Fig. 3 is a view similar to Fig. 1 but showing a changed position of certain parts, with the detent in a retracted position.

Fig. 4 is a horizontal section, taken on the line 4—4 of Fig. 2.

In the specific form herein shown, the invention is applied to a winch which is particularly adapted for attachment to railway cars for use in connection with the hand-operated brakes.

In the construction illustrated, the improved winch comprises a housing 1, in which is mounted a rotatable power transmitting element 2 adapted to be actuated by a hand lever 3.

The housing 1 is preferably a metal casting of any desired form. The housing has a peripheral flange 4, provided with apertured lugs 5 for receiving bolts or other fastening means by which the winch may be secured to a side or end of the railway car. One side of the housing is closed by a removable plate 6, which is secured to the housing by bolts or screws 7, and the lower end of the housing is open.

Extending through the housing, is a bolt 8 for rotatably supporting the improved power transmitting element 2.

In the form shown, the power transmitting element 2 includes a hub portion 85 having a drum 9 formed at one end thereof and provided with a pair of lugs 10 for attachment to one end of a cable 11 which is adapted to be partly wound on the drum when the power transmitting element 2 is rotated.

Located on one side of the drum, is a pair of substantially concentric ratchet wheels 12 and 13, adapted to be driven by pawls 14 and 15, respectively. The ratchet 12 is considerably smaller than the ratchet 13 and is mutilated so as to provide a smooth surface 16 on a portion of its periphery.

The pawls 14 and 15 are pivoted on a pin 17, which is supported in a substantially

U-shaped rocker member 18 having trunnions 19 and 20 which are journaled in the housing 1 and plate 6, respectively. The outer end of the trunnion 19 is polygonal in cross section and supports the lever 3, which is adapted to be oscillated with uniform strokes for actuating the pawls 14 and 15 to rotate the power transmitting element 2 step-by-step. A nut 21 is secured to the outer end of the trunnion 19.

A detent 22 is pivoted in the housing and is adapted to engage the ratchet 13 to prevent accidental backward movement of the drum. Formed on the detent, is an arm 23 adapted to engage a cam 24 which is formed on the rocker 18 for releasing the detent when the lever 3 is shifted to the position shown in Fig. 3.

In operation, the parts are initially in the positions shown in Fig. 1. To tighten the cable the handle lever 3 is oscillated with uniform strokes. On each stroke of the lever to the right, as viewed in Fig. 1, one of the pawls engages the corresponding ratchet for advancing the drum. On the first four effective strokes of the lever, the pawl 14 engages the ratchet 12 for advancing the drum with a rapid take-up movement. In the form shown, each tooth on the ratchet 12 corresponds to three teeth on the larger ratchet 13. When the ratchet 12 is being advanced by the pawl 14, the pawl 15 merely rides idly on the ratchet 13.

After the pawl 14 has engaged the last tooth on the ratchet 12, the subsequent effective strokes of the lever 3 will move the pawl 15 into engagement with the ratchet 13 for advancing the drum only one step at a time, which the pawl 14 rides idly on the smooth portion 16 of the ratchet 12.

With this improved construction, the winch has a differential speed, permitting a rapid and automatic take-up movement without changing the strokes of the lever.

When it is desired to release the winch, the lever 3 is moved to the extreme position shown in Fig. 2 for retracting the detent 22 by means of the cam 24.

Although but one specific embodiment of this invention is herein shown and described, details thereof may be modified without departing from the claims.

I claim:

1. A device of the class described comprising a power transmitting element, a pair of racks on said element, one of said racks being mutilated, an operating lever, and a pair of pawls on said lever, one of said pawls being adapted to engage said mutilated rack for effecting a predetermined throw of said element, the other of said pawls being adapted to engage the other rack for effecting a shorter throw of said element without changing the stroke of said lever.

2. A device of the class described com-

prising a rotatable power transmitting element, a pair of substantially concentric ratchets of different diameters on said element, the smaller of said ratchets being mutilated, an operating lever, and a pair of pawls on said lever, one of said pawls being adapted to engage said mutilated ratchet during certain strokes of said lever, the other pawl being adapted to engage the larger ratchet during certain other strokes of said lever.

3. A device of the class described comprising a rotatable power transmitting element, a pair of substantially concentric ratchets of different diameters on said element, the smaller of said ratchets being mutilated, an operating lever, a pair of pawls on said lever, one of said pawls being adapted to engage said mutilated ratchet during certain strokes of said lever, the other pawl being adapted to engage the larger ratchet during certain other strokes of said lever, a detent arranged to secure said ratchets against backward movement, and a shoulder actuated by said lever for moving said detent out of operative relation to said ratchets.

4. A device of the class described comprising a housing, a rotatable power transmitting element journaled in said housing, a pair of substantially concentric ratchets of different diameters on said element, a detent engaging the larger of said ratchets to secure said element against backward movement, the smaller of said ratchets being mutilated, a rocker member on said housing, a lever arranged to rock said member, a pair of pawls on said member, one of said pawls being adapted to engage said mutilated ratchet for effecting a predetermined throw of said element, the other of said pawls being adapted to engage said larger ratchet for effecting a shorter throw of said element without changing the stroke of said lever, and a cam actuated by said lever for releasing said detent.

Signed at Chicago this 20th day of Dec. 1930.

FRITIOF STONEBERG.
